UNITED STATES PATENT OFFICE.

JAMES A. EGAN, OF EAST ONONDAGA, NEW YORK.

FLUSH CLOSET-TANK.

1,265,890.

Specification of Letters Patent. Patented May 14, 1918.

Application filed October 1, 1915. Serial No. 53,610.

To all whom it may concern:

Be it known that I, JAMES A. EGAN, a citizen of the United States, and a resident of East Onondaga, in the county of Onondaga and State of New York, have invented a certain new and useful Flush Closet-Tank, of which the following is a specification.

This invention has for its object a flush closet tank which is particularly simple in construction, and highly efficient and durable in use, and it consists in the novel combinations and features of construction hereinafter set forth and claimed.

In describing this invention, reference is had to the accompanying drawings, in which like characters designate corresponding parts in all the views.

Figure 1 is a vertical sectional view, partly in elevation and partly broken away, of a flush closet tank embodying my invention.

Fig. 2 is a plan view thereof, the top being removed.

Fig. 3 is a section on line A—A, Fig. 2.

This flush closet tank comprises a tank or receptacle having an open uncontrolled outlet, a normally upright capsizable bucket located in the receptacle or tank, means automatically controlling the filling of the bucket with water or other fluid, and manually operable means for controlling the capsizing of the bucket.

1 designates the receptacle or tank which may be of any suitable form, size and construction, said receptacle or tank 1 having the open outlet pipe 2 in its bottom. The outlet pipe 2 extends above the bottom of the receptacle or tank 1, is open at its top, and is formed with a small horizontally or laterally extending by-pass 3, below its top and located to drain off slowly, the water remaining in the receptacle or tank 1 below the level of the upper end of the pipe 2.

4 is the normally upright capsizable bucket located in the tank or receptacle 1, the bucket 4 being here illustrated as having horizontal pivots or trunnions 5 on opposite sides thereof which are arranged in suitable bearings 6 provided on opposite sides of the tank, these bearings being preferably semi-circular so that the bucket can be readily lifted out of the receptacle or tank and replaced therein. The bucket is normally arranged in upright position and has a discharge portion arranged above and at one side of the axis of the bucket and located farther from said axis in a radial line than the outline of

the body of the bucket and the bucket is provided with a partition having an outlet therethrough located between the discharge portion and the body of the bucket to normally confine the contents of the bucket within the body of the bucket so that the bucket is held from upsetting by its contents and when a slight overturning impulse is given thereto, the water running through the outlet onto the discharge nozzle tends to upset the balance of the bucket.

The pivots 5 are so arranged relatively to the bucket 4 that the bucket 4 tends to return to its upright position and to remain in such position when filled. The empty bucket however, balances short of its upright position, as seen in Fig. 3, and is gradually returned to its upright position by the water filling into the bucket. The filled bucket is stopped in its upright position by any suitable means, and, as here shown the upper edge thereof engages lightly the inlet pipe to be described. In order to facilitate the action of the bucket, the bucket 80 is formed with a rounding arcuate wall 7 on one side of the axis of its pivots 5 and with a flat side 8 on the opposite or discharge side of said axis, the rounding wall constituting one lateral side and the bottom of 85 the bucket, and being concentric with the axis of the pivots 5, and the flat wall 8 extending inside or along a chord of the curve of the wall 7 if it were continued, and the edge of the open top also extending in a 90 plane within or in a chord of the curve of the wall 7 if extended. Hence, the bucket is cylindrical in part in the general form of a short cylinder, intersected by two planes which meet. The ends or the sides 95 from which the pivots or trunnions project are flat and are located close to the long sides of the tank or receptacle 1. The bucket 4 is also formed with a baffle plate or partition wall 9 partly closing a portion of the open top side of the bucket and extending from near the top inwardly toward the discharge wall 8, said wall 9 diverging from the open top as it approaches the wall 8 and being formed with an outlet opening 10 adjacent 100 to said side wall 8. The portion of the bucket in front of the wall 9 forms a discharge nozzle 11 arranged above and at one side of the axis of the bucket and farther from the axis in a radial line than the outline of the cylindrical part of the bucket. 110 This wall 9 prevents the water from dump-

ing out of the bucket and causes the same to run uniformly through the outlet 10 and normally confines the contents of the bucket to substantially within the body or cylindrical part of the bucket whereby the bucket is held from upsetting by its contents. The free edge 9^a of the wall 9 is located nearer the axis of the bucket than the end adjacent the wall 8, and this arrangement of 10 the wall 9 together with the construction of the bucket causes the bucket to capsize. When the bucket is capsized, after the water in the nozzle has run out, the main body of the water will run out through the outlet 10 15 instead of over the top of the wall 9 and into the tank 1, and owing to the wall 9 and the shape of the bucket, the momentum of the bucket is nearly neutralized, and the mass of water on one side, that is, the 20 outlet side of the axis of the bucket just overbalances the weight of the water on the other side, as the bucket is capsizing. Hence, the water is not discharged from the bucket faster than it can pass out through the outlet 25 2. The capsizing movement of the bucket 4 is limited by the engagement of the upper edge of the wall 7 with the inlet pipe.

The means for automatically controlling the filling of the bucket comprises a float 30 12 located in the bucket and carried by a lever arm 13 pivoted at 14 between its ends and connected to operating means 15 of the valve which controls the flow of water through the inlet pipe 16, the pivot 14 being 35 located in a bracket 17 provided on the valve casing 18.

The inlet pipe 16 extends vertically into the tank or receptacle 1 and has a laterally extending branch 19 at its upper end extending 40 over the open top of the bucket 4 and the wall 9 in position to discharge thereinto in all positions of the bucket, this branch 19 leading from the valve 18 which is located at the top of the pipe 16. The wall 45 9 is formed with a slot 20 for receiving the branch 19 during the capsizing of the bucket 4.

From the foregoing, it is obvious that the branch 19 of the inlet pipe and the connections between the float 12 and the valve, extend 50 into the bucket 4 through the open top thereof.

The manually operable means for controlling the capsizing of the bucket 4, in this 55 embodiment of my invention operates to give the initial starting movement to the bucket to capsize the same, the arrangement of the pivots 5 and of the body of the bucket being such that the bucket when filled is but 60 slightly overbalanced toward its upright position, and but slight movement overbalances the bucket toward its overturned position. Said means comprises a rock shaft 21 journaled in the front wall of the receptacle or 65 tank 1 and having a handle 22 at its outer

end, and a rock arm 23 at its inner end, which carries means as a roller 24 at its inner end, the roller riding upon the upper edge of one of the flat ends of the bucket and being movable into and out of detachable 70 engagement with the bucket 4.

In operation the bucket 4 is filled and the valve located in the casing 18 is closed by the action of the float 12. Upon the movement of the handle 22 to the left, Fig. 1, the 75 rock arm 23 of the operating means causes the roller 24 to move downwardly and to the left on the upper edge of the bucket, and to tilt the bucket so that the center of gravity is changed from the right side to 80 the left side of a vertical line passing through the pivots 5, so that the weight of the water will complete the overturning of the bucket. When the bucket is empty it rights itself automatically, and when the 85 bucket is filled the upper edge thereof near the nozzle abuts at 25 against the branch 19 of the inlet pipe.

This flush closet tank is particularly advantageous in that the bucket thereof is 90 easily capsized and overturns slowly and evenly and comes to an easy stop at both ends of its movement, and further in that by the employment of the bucket the use of a troublesome valve in the outlet is avoided. 95

What I claim is:

1. A flush closet tank comprising a receptacle or tank having an outlet and a normally upright capsizable bucket located in the receptacle or tank and being cylindrical in part and pivoted on a horizontal pivot at the axis of the cylinder, the bucket being open at its top along a non-cylindrical portion of the bucket, said non-cylindrical portion constituting an extension located at the 105 upper portion of the bucket when the latter is in upright position and at one side of its axis which extension extends outside of the cylindrical outline of the bucket, the bucket also having an internal wall extending from 110 its open side to the extension, the wall being located within the cylindrical outline of the bucket and having an opening near its lower end, and means for giving an initial capsizing impulse to the bucket, substantially as 115 and for the purpose set forth.

2. A flush closet tank comprising a receptacle or tank having an outlet, and a normally upright capsizable bucket mounted in the receptacle or tank and arranged to return to its upright position when empty and to remain in its upright position when filled, the bucket being open at its top and having a baffle plate extending from the open side to the wall on the discharge side of the 125 bucket, said plate being formed with an outlet adjacent said side wall on the discharge side of the bucket, substantially as and for the purpose specified.

3. A flush closet tank comprising a recep- 130

- tacle or tank having an outlet, a normally upright capsizable bucket mounted in the receptacle or tank and arranged to return to its upright position when empty and to remain in its upright position when filled, the bucket being open at its top and having a baffle plate extending from the open side to the wall on the discharge side of the bucket and formed with an outlet adjacent said side wall on the discharge side of the bucket, the baffle plate diverging away from the upper edge of the bucket as said plate approaches said wall on the discharge side of the bucket, substantially as and for the purpose set forth. 4. A flush closet tank comprising a receptacle or tank having an outlet, a normally upright capsizable bucket located in the receptacle or tank, the bucket being cylindrical in general form and pivoted at its axis and having a flat side and an open top side arranged in converging planes intersecting the cylinder, and a plate or wall located in the bucket, and extending from the open side toward the flat side and formed with an outlet adjacent the flat side, substantially as and for the purpose described. 5. A flush closet tank comprising a receptacle or tank having an outlet, a normally upright capsizable bucket located in the receptacle or tank, the bucket being cylindrical in general form and pivoted at its axis and having a flat side and an open top side arranged in converging planes intersecting the cylinder, and a plate or wall located in the bucket, and extending from the open side toward the flat side, and diverging from the edge at the open side as it approaches the flat side, and being formed with an outlet adjacent the flat side, substantially as and for the purpose specified. 6. A flush closet tank comprising a receptacle or tank having an outlet and a normally upright capsizable bucket located in the receptacle or tank, the bucket being cylindrical in part, and pivoted at its axis and having a substantially flat lateral side intersecting the cylindrical outline of the bucket, the straight side extending outside of the cylindrical outline of the bucket, and a baffle plate extending between the flat side and the upper side of the bucket and having an outlet therethrough, substantially as and for the purpose described. 7. A capsizable bucket pivoted on a horizontal axis and arranged to normally balance in upright position, the bucket having a discharge nozzle arranged above and at one side of its axis and arranged farther from the axis in a radial line than the outline of the body of the bucket, and a partition having an outlet therethrough located between the discharge portion and the body of the bucket to normally confine the contents of the bucket within the body of the bucket whereby the bucket is held from upsetting by its contents, substantially as and for the purpose specified. 8. A capsizable bucket pivoted on a horizontal axis arranged to normally balance the bucket in upright position, the bucket having a discharge nozzle arranged above and at one side of its axis and arranged farther from the axis in a radial line than the outline of the body of the bucket, and a partition having an outlet therethrough located between the discharge nozzle and the body of the bucket to normally confine the contents of the bucket within the body of the bucket whereby the bucket is held from upsetting by its contents, and means for giving a starting impulse to the bucket to capsize the same, said means acting directly upon the bucket, substantially as and for the purpose set forth.
- In testimony whereof, I have hereunto signed my name, at Syracuse, in the county of Onondaga, and State of New York, this 16th day of September, 1915.
- JAMES A. EGAN.
